[57] CLAIM

The ornamental design for a cam lever lock, as shown and described.

DESCRIPTION

FIG. 1 is a perspective view of a cam lever lock showing my new design;

FIG. 2 is a front elevational view of the cam lever lock of FIG. 1 depicted in its environment;

FIG. 3 is a top plan view of FIG. 2;

FIG. 4 is a rear elevational view of FIG. 2;

FIG. 5 is a left side elevational view of FIG. 2;

FIG. 6 is a right side elevational view of FIG. 2; and,

FIG. 7 is a bottom elevational view of FIG. 2.

The broken lines are shown for illustrative purposes only and form no part of the claimed design.
